US00D447957B1

(12) **United States Design Patent**
Lichtman et al.

(10) **Patent No.:** **US D447,957 S**
(45) Date of Patent: **** Sep. 18, 2001**

(54) **BOTTLE**

(75) Inventors: **Jeff Lichtman**, Chicago, IL (US); **Fred Mittelman**, Tuxedo Park, NY (US); **Sandra Blevins**, Jersey City, NJ (US)

(73) Assignee: **Stokely-Van Camp, Inc.**, Chicago, IL (US)

(**) Term: **14 Years**

(21) Appl. No.: **29/102,680**

(22) Filed: **Mar. 26, 1999**

(51) LOC (7) Cl. **09-01**

(52) U.S. Cl. **D9/556**; D9/569

(58) Field of Search D9/500, 502, 503, D9/504, 516, 520, 529, 530, 537, 538, 539, 541, 549, 556, 558, 559, 569, 574; 215/379, 382; 220/669, 670

(57) **CLAIM**

The ornamental design for a bottle, as shown and described.

DESCRIPTION

FIG. 1 is a perspective view of a bottle showing a new design;

FIG. 2 is a front elevational view of the bottle depicted in FIG. 1, the opposite rear elevational view being identical; FIG. 3 is a side elevational view of the bottle depicted in FIG. 2, representing a partial rotation of the bottle about its vertical center axis from the front elevational view depicted in FIG. 2, the opposite side elevational view being identical; FIG. 4 is a top plan view of the bottle depicted in FIG. 2; and,

FIG. 5 is a bottom plan view of the bottle depicted in FIG. 2.

The broken line environmental showing is for illustrative purposes only and does not form part of the claimed design.
